(57) **CLAIM**

The ornamental design for the 3 tier riser, as shown and described.

DESCRIPTION

FIG. 1 is a front perspective view of a 3 tier riser, showing my new design;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a left-side elevational view of the invention, the right-side elevational view being a mirror image thereof.

1 Claim, 6 Drawing Sheets*FIG. 1*

FIG. 2

FIG. 3

FIG. 4

FIG. 5
